FASTENER-APPLYING IMPLEMENT

Arthur H. Maynard, Warwick, R. I., assignor to
 Boston Wire Stitcher Company, Portland,
 Maine, a corporation of Maine

Application April 5, 1933, Serial No. 664,568

25 Claims. (Cl. 1-3)

This invention relates to improvements in stapling implements or tackers for use in attaching tags and labels to boxes and cases, for tacking papers or drawings to a board and for securing 5 various other articles to different objects.

One object of the invention is to provide a simple, compact appliance of the type indicated which is convenient to operate and efficient in use for the purposes specified.

10 Another object of the invention is to provide an implement of the type indicated having a magazine with a gate or door adapted to be opened to permit loading the machine with staples or other fasteners and in which is incorporated 15 means for guiding the fasteners in driving them into the work.

Another object of the invention is to provide an implement of the type indicated having automatically-operated means for gripping the staples 20 when the gate is opened to prevent them from being expelled from the magazine by the feeding means.

Another object of the invention is to provide an implement of the type indicated having means 25 for withholding the staple-gripping means from engagement with the staples when it is desired to remove the staples from the magazine.

Another object of the invention is to provide an implement of the type indicated having its 30 magazine and staple-feeding mechanism embodied in a unit adapted for convenient application to and removal from the main frame of the device so that other units may be substituted therefor to render the appliance capable of operating on different sizes of staples.

Another object of the invention is to provide an implement of the type specified having its parts designed for economical manufacture and 35 convenient assembly.

40 Another object of the invention is to provide an implement of the type indicated which is strong and staunch in structure and proof against derangement or getting out of order under rough handling in use.

45 Further objects of the improvement are set forth in the following specification which describes a preferred embodiment of the invention, by way of example, as illustrated by the accompanying drawings. In the drawings:

50 Fig. 1 is a side elevation of a stapling implement or tacker embodying a preferred form of construction of the invention;

Fig. 2 is a similar view of the implement, part 55 sectional in a medial longitudinal plane;

Fig. 3 is a sectional plan view of the lower por-

tion of the implement taken on line 3-3 of Fig. 1;

Fig. 4 is a front elevation of the implement;

Fig. 5 is a sectional view of the magazine of the implement taken on line 5-5 of Fig. 1;

Fig. 6 is a sectional view of the fore part of the implement showing the gate opened to permit loading the magazine with staples and illustrating the manner in which the staples are held therein by means of the retainer-pawl;

Fig. 7 is a front view of the main frame of the implement;

Fig. 8 is a perspective view of the staple-core and its holder;

Fig. 9 is a perspective view of the magazine 15 gate; and

Fig. 10 is a side view of the front end of the implement showing a modified form of construction.

The invention consists in a stapling implement 20 or tacker adapted to be conveniently held in the hand to be placed against the work and having means operated from a plunger to drive the staples, tacks or other fasteners into the work. The implement is provided with a magazine for 25 containing a supply of staples or the like and automatically-operated means for successively feeding the staples or other fasteners to the driving means. A gate at the end of the magazine provides for conveniently loading the implement with fasteners without the necessity of removing the staple-feeding mechanism, and means cooperating therewith act to retain the unused staples in the magazine to prevent them from being discharged therefrom during the 35 reloading operation.

Referring to the drawings, the implement as herein illustrated comprises a main frame 2 which may be constructed in the form of a die-casting to render it economical to manufacture 40 without machining operations. The frame 2 is constituted by a base 3 provided on its bottom with longitudinally-extending side-flanges or feet 4 and having a head-portion or housing 5 rising from its forward end. The head 5 and base 3 are connected by a suitable handle-portion 6 which provides a grip for holding the implement and applying it to use. The base 3 of the frame 2 is cored out to form a longitudinal cavity or pocket 7 which extends from end to end there- 45 of and is closed at its rearward end by a wall 8. Removably held in the cavity or pocket 7 is a staple-core 10 for supporting the staples in alined relationship in the magazine. A staple-pusher 50 55 is mounted to slide on the core 10 to propel

the staples therealong whereby to successively feed them to the staple-driving means in the head 5.

Referring to Fig. 8, the staple-core 10 is preferably constructed from sheet-metal, being of substantially U-shape or trough-form with a bottom 11 and opposite side walls 12 rising therefrom. The side walls 12 are bent or folded inwardly at the rearward end of the core to provide rests or abutments 13 against which a rectangular block or plate 14 seats, the block being shown in full lines in Fig. 2 and indicated by dot-and-dash lines in Fig. 8. Ears 15 sheared from the metal of the side walls 12 of the core 10 are bent inwardly with their edges in position to hold the block 14 against the abutments 13. The block 14 is provided with a threaded hole 16 for receiving the end of a screw, to be later described, which secures the core in place in the frame 2. One of the side walls 12 of the core is provided near its forward end with an ear 17 projecting inwardly to serve for a purpose as later explained.

The forward ends of the side walls 12 of the core 10 are cut away at the bottom to provide a recess for the gate which closes the end of the magazine; the upper overhanging portions 18 of the walls forming guides for the staples as they are fed off from the core and driven down into the work in the manner as later more fully explained. Extending between the sides of the core 10 and riveted to the walls thereof is a cross-pin 19, on which is rotatably mounted a roller 20 used as a support for a helical wire spring 21 which is connected to slide the staple-pusher 25 on the core to feed the staples therealong.

The staple-pusher 25 is of conventional form as constructed from a sheet-metal strip bent into inverted U-shape to adapt its sides to straddle the sides of the core 10 to slide thereon. At the rearward end of the pusher 25 is an ear 23 bent down between its sides and formed with an aperture through which is hooked the end of the helical spring 21. The spring 21 extends forwardly and passes down around the roller 20 with its rearward end fastened to a lug or finger 22 sheared from the bottom wall of the core 10 and bent upwardly therefrom to engage the end loop of the spring. It will be apparent that as the spring 21 draws the staple-pusher 25 forwardly on the core 10 its coils will readily pass over the roller 20 as the spring is contracted in length.

The core 10 and the assembled staple-feeding means, consisting in the pusher 25 and spring 21, are assembled in the frame 2 as a unit in the manner as next explained. Welded or otherwise suitably secured to the bottom wall 11 of the core 10 is a flat strip of sheet-metal constituting a base-plate 26, the lateral edges of which are bent or curled around to provide runners 27 adapted to engage over the longitudinally extending side flanges 4 of the frame 2, see Figs. 3, 4, 7 and 8. Preferably, the upper edges of the longitudinal flanges 4 are recessed at 28 as shown in Fig. 7 to receive the edges of the runners whereby to form a smooth, flush joint. The base-plate 26 projects rearwardly in a tongue-portion 29 which is adapted to seat in a notch or recess 9 formed in the bottom of the rearward end of the frame 2, see Figs. 2 and 3 of the drawings. The staple-core 10 is assembled in the frame 2 by simply sliding its runners 27 along the side-flanges 4 thereof until the end of the tongue 29 on the base-plate 26 seats in the notch 9. A screw 30

is inserted through an aperture in the end wall 8 of the frame 2 with its head countersunk therein and by screwing its threaded end into the block 14 the core is secured fixedly in place within the bottom cavity or pocket 7 which forms the magazine for the staples.

It will be noted from Figs. 1 and 2 of the drawings that the lower side walls of the frame 2 are cut back from in under the head 5 so that the staple-core 10 and its base-plate 26 project forwardly therebeyond. It will also be observed by reference to Fig. 8 that the forward portion of the base-plate 26 is beveled off and narrowed along its sides, this provision being made to adapt the gate for the magazine to close down over the forward end of the core in the manner as later explained.

Extending vertically within the head 5 of the frame 2 is a bore 32, in which is slidably mounted a plunger 33. The lower end of the plunger 33 is slotted diametrically at 34 to adapt it to receive the upper end of a staple-driver 35 which is constituted by a flat, hardened plate or blade. A stud 37 inserted through a vertical slot 39 in the front of the head 5 and a bore in the forward side of the plunger 33 has its reduced threaded end 36 projecting through an aperture in the staple-driver and screwed into a hole in the plunger. The staple-driver 35 extends vertically below the plunger 33 with its rearward face in line with the edges of the forwardly projecting portions 18 on the end of the staple-core 10. Normally, the lower edge of the driver is raised above the top of the core 10 as shown in Fig. 6 to adapt it to be slid down to impinge against the head of a staple fed off from the core to drive the latter down into the work. The plunger 33 is reciprocated in the head 5 under the pressure of the hand on a knob or hand-rest 40 secured to its upper end. The plunger 33 is held in raised position under the force of a helical wire spring 41 coiled around its upper portion and bearing against the top of the head 5 and the underside of the knob 40. The upward movement of the plunger 33 under the pressure of the spring 41 is limited by the engagement of the stud 37 with the end of the slot 39 in the head 5, it being understood that the stud slides vertically in the slot 39 during the reciprocation of the plunger. The staple-driver 35 is arranged to slide down through a throat or guideway in the gate 45 which is constructed in the manner as next described.

Referring to Fig. 9 of the drawings, the gate 45 is preferably constructed of sheet-metal shaped to form a forward wall 46 with side walls 47 projecting at right-angles thereto. The upper portions of the side walls 47 take the form of ears 48 pierced with apertures 49 by means of which the gate is hinged to the head 5. As shown most clearly in Figs. 3 and 7, the forward end of the head 5 is provided with a rectangular opening 43, to the sides of which the ears 48 of the gate 45 are pivoted by means of a cross-pin 50. The pin 50 extends through the sides of the head 5, being formed with an enlarged head 51 fitted to a hole in one side of the head and having a reduced portion 52 projecting axially therefrom. The head 51 of the pin 50 abuts the side of one of the ears 48 on the gate 45 to restrain it from longitudinal movement in one direction and a flat spring 53 is employed for preventing the withdrawal of the pin in the opposite direction. The spring 53 is pivoted to the side of the head 5 by means of a rivet 54 with its lower end perforated 75

to receive the projection 52 on the head 51 of the pin 50. The lower end of the spring 53 may be sprung outwardly and swung to one side to permit removal of the pin 50.

5 The lower portion of the gate 45 has its sides bent around or folded inwardly to form lugs or abutments 55 overlying the face of its front wall 46 in spaced relation thereto to provide a throat with guideways 58 through which the staples slide as they are driven down under the force of the driver 35. The bottom portion of the gate 45 is preferably narrower than its upper part and of such width as to cause its sides to apply frictional resistance to the passage of the staples 10 through the guideways 58 whereby to prevent them from dropping down through the gate before they are acted on by the driver. The abutments or lugs 55 are adapted to seat in the recessed forward end of the staple-core 10 beneath the projecting upper portions 18 of its side walls 12 when the gate is in closed position as shown in Figs. 1 and 2 of the drawings.

The gate 45 is maintained in closed position and also held in open position by means yieldably engaged with the edges of its hinge-ears 48. For this purpose the edges of the ears 48 are formed with arcuate cam-faces 56 merging into flat beveled faces 57 as shown most clearly in Fig. 9 of the drawings. Referring to Figs. 2 and 3 of the drawings, a plunger-block 60 slideable in a slot 61 in the head 5 of the machine is operated by springs 62 to cause its forward beveled face 63 to act against the faces 56 and 57 of the hinge-ears 48 of the gate 45. The springs 62 are pocketed in bores 64 in the block 60 with their rearward ends bearing against the end of the slot 61 to press the block forwardly. With the beveled face 63 of the block bearing against the beveled edges 57 on the ears 48 of the gate the latter is maintained in closed position with its lugs 55 abutting the forward recessed end of the staple-core 10. The gate 45 may be opened manually by swinging it on its pivot-pin 50, the beveled faces 57 of the ears 48 causing the block 60 to slide rearwardly to eventually engage its beveled forward face 63 with the arcuate edges 56 of the hinge-ears as shown in Fig. 6. In this latter position the spring-pressure of the plunger-block 60 acts to frictionally hold the gate open.

50 Projecting forwardly within the lower opening 43 of the head 5 is a rectangularly-shaped tongue 65, see Fig. 7, having its opposite faces spaced away from the sides of the opening to accommodate the ears 48 of the gate 45 therebetween; it being noted that the tongue is provided with a lateral hole 66 through which the pivot-pin 50 for the gate extends. The forward face of the tongue 65 forms a rest or bearing for the staple-driver 35 to take the rearward thrust thereof and steady it during its reciprocation. The main purpose of the tongue 65, however, is to serve as a support for a retainer-pawl 70 which operates as a check or detent to prevent the staples from being ejected from the end of the magazine when the gate 45 is opened. The tongue 65 is formed with a central vertical slit 67 for receiving the flat sheet metal pawl 70 which is pivotally mounted on the pin 50 for the gate 45.

70 The pawl 70 has a pointed toe 71 overlying the top of the staple-core 10 and adapted to engage with the crossbars or heads of the staples 3 straddled across the core. The toe 71 of the pawl 70 is carried into engagement with the heads of the staples under the pressure of a plunger-pin 72 slidably mounted in a bore 73 in the head 5 with

its end engaging the vertical edge of the pawl; a helical spring 74 pocketed in the bore 73 acting against the rearward end of the plunger-pin to project it forwardly to act on the pawl.

When the gate 45 is closed the pawl 70 is automatically released from the staples to allow them to be fed forward on the core, the means for performing this function being arranged as next described. The pawl 70 has an upward projection or head 75 formed on its rearward edge 10 with a beveled face 76 corresponding to the beveled edges 57 on the ears of the gate 45. The beveled edge 76 is adapted to be engaged by the forward beveled face 63 of the plunger-block 60 when the latter is slid forward from the position shown in Fig. 6 to that illustrated in Fig. 2 during the closing of the gate 45. This engagement of the block 60 with the beveled edge 76 of the head 75 rocks the pawl 70 to lift its toe from engagement with the heads of the staples 3 as clearly illustrated in the view last referred to.

In some instances it may be desired to remove unused staples from the magazine of the implement and to accomplish this purpose the pawl 70 may be released by manual means as next described. Referring particularly to Figs. 2 and 6 of the drawings a plunger-pin 80 is mounted in a horizontal bore 81 in the lower part of the head 5 just above the base-portion 3 of the frame 2 with its rearward end projecting into position to be engaged with a finger of the hand. The forward end of the pin 80 has an enlarged head 82 seated in a counterbore 83 and formed with a beveled, projecting end 84. The beveled end 84 of the pin 80 projects into an angular notch 85 formed in the rearward portion of the pawl 70. The notch 85 is so shaped that its edges are normally clear of the beveled end of the plunger-pin 80. When the gate 45 is open, however, and the pawl 70 in position with its toe 71 engaging the head of a staple the plunger-pin may be manually pushed forwardly to engage its end with the uppermost edge of the notch whereby to rock the pawl to release it from the staples to permit their withdrawal from the magazine.

The method of operation of the implement is as next explained: To load the magazine with staples the gate 45 is opened by grasping its sides and swinging it outwardly to the position illustrated in Fig. 6. As the gate is swung open in this manner the beveled faces 57 on its ears 48 cam against the beveled face 63 of the block 60 to force the latter rearwardly in its slot 61. Thereafter, the arcuate faces 56 on the ears 48 ride on the beveled face 63 of the block 60 and the frictional engagement therebetween tends to hold the gate in open position as shown in Fig. 6 of the drawings. The retraction of the plunger-block 60 removes its pressure on the beveled edge 76 of the head 75 of the pawl 70 and thereupon the plunger-pin 72 acts on the toe 71 of the pawl to engage it with the head of one of the staples 3 if any remain on the core 10. Should there be no staples in the magazine the pusher 25 will have been drawn forward until its rearward finger 23 engages the inwardly projecting ear 17 on the side of the core 10 so that the pusher is prevented from sliding off the end of the core.

The staples are usually packaged in strip or stick form with their heads cemented or otherwise fastened together to adapt them to be individually broken away from the strip. Supplied in this form as a refill the stick may be inserted into the magazine of the implement by simply

placing its end on the core 10 and pushing it inwardly to slide the staple-pusher 25 rearwardly against the tension of its spring 21. As the staple-stick is inserted into the magazine in this manner 5 the toe of the pawl 70 rides across the heads of the staples s to prevent the stick or refill from being forcibly ejected from the magazine when pressure on its end is released. After the stick has been slid clear into the magazine the gate 45 10 is closed by merely swinging it down against the front of the core 10. As the gate 45 is swung down into closed position as shown in Fig. 1 the arcuate edges 56 of its ears 48 ride across the end of the plunger-block 60 to allow the latter to slide forwardly with its beveled face 63 engaging the beveled edges 57 of the ears 48. The pressure of the plunger-block 60 under the force of its spring 62 thus has the effect to resist the opening movement of the gate 45 to hold it firmly 15 in place, closed against the end of the core 10. As the plunger-block 60 slides forwardly upon the closing of the gate 45 its beveled face 63 comes into engagement with the beveled face 76 on the retainer-pawl 70, thereby acting to rock the latter to free its toe 71 from the staples s on the core 10. The staples are thus released to allow them to be slid forward by the pusher 25 until the foremost staple in the strip brings up 20 against the forward wall 46 of the gate 45. In this position the forward staple is located beneath the bottom edge of the driver 35 to adapt it to be driven down through the guideways 58 in the gate 45.

In applying the implement to use the operator 25 grasps the handle 6 and places the bottom of its flat base 3 against the work to be stapled. While holding the implement in this position the other hand is pressed against the knob 40 to slide the plunger 33 down through the bore of the head 5. 30 As the driver 35 is thus caused to descend its lower edge impinges against the head of the foremost staple s to drive the latter down through the throat of the gate 45 and into the work. After the staple has been driven into the work 35 pressure on the knob 40 is released, whereupon the plunger 33 will be returned to first position by the recoil of its spring 41. As the staple-driver 35 is elevated above the top of the core 10 the staples are again fed forward by the pusher 25 to 40 locate the foremost one beneath the bottom edge of the driver; the operation of applying the staples being continued in this way until the supply 45 in the magazine is exhausted.

If the supply of staples is replenished when 50 only a few remain in place on the core 10, such unused staples are prevented from being ejected from the magazine even though the last one in the series has been fed forwardly beyond the toe of the pawl 70. To provide for this contingency the staple-pusher 25 is scored on its top with serrations 88 which are engaged with the toe of the pawl in the same manner as the heads of the staples. 55

The implement is ordinarily fitted with a predetermined size of staple-core and the other parts made complementary thereto for use with the desired size of staple. When it is required to use wider or narrower staples the magazine and its assembled staple-feeding means may be removed from the machine and another unit of different size substituted therefor. The magazine may be easily removed from the implement by releasing its holding screw 36 and sliding it out from the front of the cavity or opening 7. It will be understood that to remove the magazine the pawl 60

70 must be released from the staple-pusher 25 and this is readily accomplished by manually sliding the plunger-pin 80 to cause its beveled end to act on the edge of the notch 85 in the pawl to lift its toe in the manner as previously explained. It should be noted that when a core is replaced with one of different width to adapt the implement for wider or narrower staples, as the case may be, the driver-plate 35 and the gate 45 must also be replaced with others of the appropriate 10 dimensions.

Fig. 10 of the drawings illustrates a modified form of construction of the gate for the magazine of the implement. Whereas, in the form of construction previously described the bottom of the 15 gate 45 is flush with the flat base of the implement, in the modified construction shown in Fig. 10 the gate projects below the base to adapt it to be inserted into a groove or opening in the object to be stapled. For example, with this type of 20 gate the implement may be used for stapling or tacking upholstery binding tape and similar materials to furniture, automobile interiors and the like. The method of operation of the implement having the gate constructed in accordance with 25 this last described form is substantially the same as previously explained. That is to say, the binding tape or other strip material t is placed in position on the object to which it is to be attached and the bottom of the gate 45 is then inserted 30 between its folds in the manner as illustrated in Fig. 10. The staples s may be driven through the tape by operating the implement in the manner as above explained while sliding it lengthwise of the tape after each operation without removing the threated end of the gate therefrom. 35

It will be observed from the foregoing that the present invention provides a conveniently operated implement for applying staples and other forms of fasteners to attach various objects and 40 articles and for other types of work. The novel form of construction of the implement provides the advantages hereinbefore particularly pointed out and further renders it most efficient for the purposes set forth and durable in use over long 45 periods.

While the implement is herein described and illustrated as embodied in a preferred form of construction, various modifications may be made in the structure and arrangement of its parts 50 without departing from the spirit or scope of the invention. Therefore, without limiting myself in this respect,

I claim:

1. In an implement of the type indicated, the 55 combination of a frame having a substantially flat base with a longitudinal slot open on its under side, fastener-applying means carried by said frame, a core adapted to support a series of fasteners to successively feed them to the applying means, said core having runners on its sides, and means on the outer sides of the base of the frame engageable with the runners by sliding the core into the slot to support the core in operative position on the frame.

2. In an implement of the type indicated, the 60 combination of a frame having a relatively flat base with a longitudinal slot open on its under side, fastener-applying means carried by said frame, a core adapted to support a supply of fasteners in position to be fed to the applying means, said core being slideable into the longitudinal slot in the base of the frame, means interengageable 65 between the sides of the core and the outer sides of the base to support the core in position in the 70 75

slot in the base, a pusher slideable on the core to feed the fasteners therealong, and a spring enclosed within the core and anchored thereto at one end with its opposite end attached to the 5 pusher to slide the latter on the core.

3. In an implement of the type indicated, the combination of a frame having an upper handle and a channeled base therebelow formed with a longitudinally-extending chamber on its under 10 side providing a magazine for fasteners, said base also provided with longitudinally extending projections on its sides, fastener-applying means carried on said frame, a core adapted to be inserted into the chamber and formed with lateral 15 projections shaped to embrace the projections on the sides of the base of the frame to adapt it to be removably positioned in the chamber to support a series of fasteners in the magazine, and means for sliding the fasteners on the core to feed 20 them successively to the applying means.

4. In an implement of the type indicated, the combination of a frame formed with a longitudinally-extending walled chamber having flanges projecting laterally from its sides, fastener-applying means carried by the frame, and a core having laterally projecting runners shaped to embrace the flanges on the frame to adapt it to be inserted 25 into the chamber thereof to support a series of fasteners for delivering them successively to the 30 applying means.

5. In an implement of the type indicated, the combination of a frame having a longitudinally-extending chamber on its under side, flanges projecting from the side walls of the chamber, fastener-applying means carried by the frame, and a core for supporting a series of fasteners in position to be fed therealong and having runners slidably engageable with the flanges on the side walls 35 of the chamber to adapt it to be removably positioned therein.

6. In an implement of the type indicated, the combination of a frame formed with a longitudinally-extending chamber with flanges on its sides, fastener-applying means carried by the frame, 40 and a core having opposite parallel sides adapted to be positioned in spaced relation to the sides of the chamber in the frame, said core having runners engageable with the flanges on the sides of the chamber to adapt the core to be slid into 45 position therein.

7. In an implement of the type indicated, the combination of a frame having a cavity on its under side with flanges projecting laterally from the walls thereof, fastener-applying means carried by the frame, and a core for supporting a series of fasteners slidably mounted thereon, said core comprising a base-plate having runners on 50 its sides slidably engageable with the flanges on the frame and formed with upstanding side walls adapted to be entered into the chamber of the frame in spaced relation to the walls thereof.

8. In an implement of the type indicated, the combination of a frame having a chambered bottom with flanges projecting laterally from its sides, fastener-applying means carried by the frame, and a core comprising a flat base-plate adapted to underlie the bottom of the frame and having runners on its sides for engaging around the flanges thereon, said core comprising a trough-shaped structure secured to the base-plate with its lateral walls adapted to be positioned in spaced relation to the walls of the chamber in the frame.

9. A unitary supply-holder and feeding means 75 for fastener-applying implements comprising a

core having a bottom wall and upstanding spaced side walls, a pusher adapted to straddle the walls of the core to slide on the upper edges thereof and provided with an ear projecting downwardly therebetween, and a spring attached to the ear on the pusher and extending therefrom within the side walls of the core with its opposite end anchored therein to cause it to draw the pusher along the core.

10. A unitary supply-holder and feeding means 10 for fastener-applying implements comprising a core having a bottom, spaced side walls projecting upwardly therefrom and a cross member extending therebetween at one end of the core, a pusher of inverted U-shape adapted to straddle 15 the sides of the core to slide therealong, and a spring attached to the rearward end of the pusher and extending between the side walls of the core around the end member thereof with its opposite end secured to the rearward end of the core. 20

11. In an implement of the type indicated, the combination of a frame having a head formed with a bore and a slot in the side of the head opening into its bore, a plunger slideable in said bore and provided with a diametrically-arranged 25 axially extending slot, a driver-blade held in said slot in the plunger, and a stud extending through the slot in the side of the head with its end engaging through axially aligned holes in the plunger and driver-blade. 30

12. In an implement of the type indicated, the combination of a frame having an upstanding head at one end formed with a vertical bore and a vertical slot in the side of the head opening into the bore, a plunger slideable in said bore and formed with a diametrical slot at its lower end, a driver-blade inserted into said slot in the plunger, a stud extending through the slot in the side of the head and through holes in the plunger and blade to secure the latter to the plunger, a knob 35 on the upper end of the plunger, and a spring acting between the head and the knob to maintain the plunger normally in raised position with the stud engaging the upper end of the slot in 40 the head. 45

13. In an implement of the type indicated, the combination of a frame having a magazine for containing a supply of fasteners, a driver reciprocable on said frame across the end of the magazine, means for successively feeding the fasteners 50 in the magazine to deliver them into position beneath the driver, and a gate hinged to the frame to close the end of the magazine and provided with a relatively narrow throat for receiving the fasteners and guiding them at their forward and 55 rearward sides as they are driven down through the gate and into the work.

14. In an implement of the type indicated, the combination of a frame having a magazine for containing a supply of staples, a core in the 60 magazine for supporting the staples in aligned relationship to adapt them to feed therealong, a staple-driver reciprocable across the end of the magazine to act on the staples fed therefrom, and a gate for closing the end of the magazine, said 65 gate having a restricted passageway with forward and rearward walls between which the staples are guided in applying them to the work.

15. In an implement of the type indicated, the combination of a frame having a magazine for 70 containing a supply of staples, a staple-driver reciprocable on the frame, a core within the magazine for supporting the staples in position to deliver them beneath the staple-driver, and a gate for closing the end of the magazine, said 75

- gate having narrow guideways at its sides of a width substantially equal to the thickness of the staple-driver through which the staples are driven in applying them to the work.
5. 16. In an implement of the type indicated, the combination of a frame having a magazine for containing a supply of staples, a staple-driver reciprocable on the frame, a core in the magazine for supporting the staples in alined relationship to adapt them to be successively fed beneath the staple-driver, a gate hinged to the frame and provided with a front wall for closing the end of the magazine and abutments spaced rearwardly from said front wall a distance substantially equal to the thickness of the staples to form narrow guideways for the staples as they are driven down through the gate.
10. 17. In an implement of the type indicated, the combination of a frame having a magazine for containing a supply of fasteners, said magazine being open at one end for the insertion of a supply of the fasteners, means reciprocable on the frame for applying the fasteners to the work, a gate hinged to the frame to adapt it to close the open end of the magazine, a plunger engaging the gate in one position to maintain it closed and in another position to hold it open, and resilient means for operating the plunger.
15. 18. In an implement of the type indicated, the combination of a frame having a magazine for containing a supply of fasteners, said magazine being open at one end for the insertion of a supply of the fasteners, means reciprocable on the frame for applying the fasteners to the work, a gate hinged to the frame to adapt it to close the open end of the magazine, said gate formed with cam-faces, a slideable plunger adapted to engage the cam-faces on the gate to maintain it in either closed or open position, and a spring for sliding the plunger.
20. 19. In an implement of the type indicated, the combination of a frame having a magazine for containing a supply of fasteners, said magazine being open at one end for the insertion of a supply of fasteners, fastener-applying means carried by the frame, a gate pivoted to close against the open end of the magazine and formed with a cam-face, a plunger adapted to cam against said face on the gate to hold the latter in closed position, and resilient means for operating the plunger.
25. 20. In an implement of the type indicated, the combination of a frame having a magazine for containing a supply of fasteners, fastener-applying means carried by said frame, a gate having ears pivoted to the frame and said ears formed with arcuate and beveled cam-faces, a plunger slideable on the frame and formed with a beveled face adapted to engage the beveled faces on the ears of the gate to hold the latter in closed position and to ride onto the arcuate faces on the ears to maintain the gate in open position, and a spring for sliding the plunger.
30. 21. In an implement of the type indicated, the combination of a frame having a magazine for containing a supply of fasteners, fastener-applying means carried by said frame, means for feed-
5 ing the fasteners in the magazine to deliver them to the applying means, a gate for closing the end of the magazine, retainer-means operative when the gate is opened to prevent the fasteners from being expelled from the magazine, and manually-operable means for releasing the retainer-means while the gate is open whereby to permit withdrawal of the fasteners from the magazine.
35. 22. In an implement of the type indicated, the combination of a frame having a magazine for containing a supply of fasteners, fastener-applying means carried by said frame, means for feed-
10 ing the fasteners in the magazine to deliver them to the applying means, a gate for closing the end of the magazine, a pawl engageable with the fasteners upon the opening of the gate to prevent them from being expelled from the magazine, and manually-operable means for releasing the pawl to permit removal of the fasteners from the mag-
15 aze.
40. 23. In an implement of the type indicated, the combination of a frame having a magazine for containing a supply of fasteners, fastener-applying means carried by the frame, means for feed-
20 ing the fasteners in the magazine to deliver them to the applying means, a gate for closing the end of the magazine, said gate formed with a cam-face, a retainer-pawl engageable with the fasteners to prevent their expulsion from the mag-
25 aze when the gate is open, said pawl formed with a cam-face conforming substantially to the cam-face on the gate, and a plunger slideable on the frame to engage the cam-faces on the gate and pawl, said engagement acting to normally 30 maintain the gate in closed position and the pawl released from engagement with the fasteners.
45. 24. In an implement of the type indicated, the combination of a frame having a magazine for containing a supply of fasteners, fastener-applying means carried by said frame, means for feed-
30 ing the fasteners in the magazine to deliver them to the applying means, a gate hinged to the frame to adapt it to close against the end of the magazine and formed with a cam-face, a pawl piv-
35 otted to the frame to adapt it to engage the fasteners to prevent them from being expelled from the magazine when the gate is opened, said pawl having a cam-face adapted to aline with the cam-face on the gate, resilient means for operating the pawl, a plunger slideable on the frame and having a beveled face engaging the cam-faces on the gate and pawl, and a spring for sliding the plunger.
50. 25. A fastener-applying implement having a magazine for fasteners, means for applying the fasteners to the work, means for feeding the fasteners to the applying means, a closure for the magazine, means for retaining the fasteners in the magazine when the closure is opened, and means for releasing said last-named means while the closure is open to permit withdrawal of the fasteners from the magazine.

ARTHUR H. MAYNARD.
